UNITED STATES PATENT OFFICE.

GEORGE E. SAVAGE, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A SHELF FOR CHAFING-DISH-LAMP SUPPORTS.

SPECIFICATION forming part of Design No. 35,361, dated December 8, 1901.

Application filed October 14, 1901. Serial No. 78,665. Term of patent 7 years.

To all whom it may concern:

Be it known that I, GEORGE E. SAVAGE, a citizen of the United States, residing at Meriden, New Haven county, Connecticut, have 5 invented and produced a new and original Design for a Shelf for Chafing-Dish-Lamp Supports, of which the following is a full, clear, and exact description.

My invention relates to a new and original 10 design for a lamp-supporting shelf or ring for chafing-dishes and the like.

In the drawings, Figure 1 is a plan view of my design. Fig. 2 is a vertical sectional view of the same.

15 The design consists of a graceful and symmetrically-formed annular shelf used to support a lamp and adapted to be attached between the legs of a chafing-dish.

The shelf in cross-section is thin. At the

central portion A it is highest and slopes 20 downwardly and outwardly in curves to the rim B. Intermediate the upper and outer portions is a slight depression C.

The leading feature of my design is the formation of an annular shelf having an inner 25 edge A, an outer rim B, and an intermediate depression C.

What I claim is—

The design for a shelf for a chafing-dish-lamp support, substantially as herein shown 30 and described.

Signed at Meriden, Connecticut, this 11th day of October, 1901.

GEORGE E. SAVAGE.
